(57) **CLAIM**

The ornamental design for a sweater shaped greeting card, as shown and described.

DESCRIPTION

FIG. 1 is a perspective view of the sweater shaped greeting card with the hanger in a first position showing our new design;

FIG. 2 is a front view thereof;

FIG. 3 is a rear view thereof, in closed position;

FIG. 4 is a right side view thereof;

FIG. 5 is a left side view thereof;

FIG. 6 is a top view thereof;

FIG. 7 is a bottom view thereof;

FIG. 8 is a rear perspective view thereof, in an open position; and,

FIG. 9 is a perspective view thereof; with the hanger in a second position.

The broken line showing of portions of the sweater shaped greeting card is included for the purpose of illustrating environmental structure and forms no part of the claimed design.
